UNITED STATES PATENT OFFICE.

WALTER H. BOWMAN, OF BRIDGEPORT, CONNECTICUT.

FIRE-ALARM.

1,162,020.

Specification of Letters Patent. Patented Nov. 30, 1915.

Application filed May 28, 1915. Serial No. 30,960.

To all whom it may concern:

Be it known that I, WALTER H. BOWMAN, a citizen of the United States, residing at Bridgeport, county of Fairfield, State of Connecticut, have invented an Improvement in Fire-Alarms, of which the following is a specification.

This invention has for its object to provide a fire alarm adapted for general use and especially adapted for use in connection with the telephones of an independent system, as in hotels, apartments, factories, school houses, &c.

A further object of the invention is to produce a fire alarm which shall be durable and reliable, will not require attention and shall be so inexpensive to produce as to place it within the reach of those using a small tenement or even a single room, and so easy 20 to attach that any person, skilled or unskilled, may install it with no other tool than a screw driver.

With these and other objects in view, I have devised the novel fire alarm which I 25 will now describe, referring to the accompanying drawing forming a part of this specification and using reference characters to indicate the several parts:

Figure 1 is an elevation showing the application of the invention to an ordinary desk telephone; Fig. 2 an elevation of the case with the cap and retaining material in section; Fig. 3 a similar view with the case in section, showing the spring in elevation; Fig. 4 a section of a slightly variant form 35 of cap. Fig. 5 a plan view of the alarm and a clamp for attachment to a desk telephone; Fig. 6 an elevation of the alarm and a bracket for securing it to a wall or fixture.

My novel alarm comprises simply a case made of metal or any suitable material and open at one end, a spring in said case, an alarm cap for the closed end having a depending flange, and low melting material 40 between the flange and the case for retaining the cap in place at all temperatures below its melting point. Should the temperature of the air be raised sufficiently to melt the retaining material, the spring will lift the cap and produce an alarm which may be caused by any suitable auxiliary means.

10 denotes the case, 11 the spring and 12 the cap which is preferably provided with a central depression or thickened portion 13 which passes into the open end of the case 55 and centers the cap thereon.

14 denotes a depending flange at the edge of the cap which in the assembled position lies at a slight distance from the case, leaving a ring-shaped space between the flange 60 and the case, which is filled with a low melting retaining material indicated by 15. Any suitable retaining material may be used, as sealing wax or any low melting compound or metallic alloy. The outer surface of the 65 case at its upper end or the inner face of the flange, either or both, may be knurled, cross-hatched or otherwise roughened for engagement by the retaining material. It should be understood that by the term "melting" I 70 mean a sufficient softening of the retaining material to weaken it so that the spring will overcome the resistance thereof and dislodge and raise the cap.

In Fig. 1, I have illustrated the use of my 75 novel alarm in connection with an ordinary desk telephone. This use of the alarm will be found very serviceable in hotels, apartment houses, factories, school houses, or wherever there are a number of rooms, 80 apartments or floors using a central telephone system having an attendant.

16 denotes the standard of a telephone, 17 the spring-controlled arm and 18 the receiver which is hung upon the arm and retains the arm in the circuit closing position against the spring, which is not shown, as it specifically forms no portion of the present invention. As an inexpensive and convenient means of securing the alarm to the 90 standard of the telephone, I provide a spring clamp comprising an eye 19 which grips the case closely and arms 20 adapted to inclose the standard of a telephone and a nut and screw indicated by 21 by which the 95 clamp with the alarm held thereby is secured in place.

The operation will be obvious. A retaining material is of course used that will melt or soften appreciably at a predetermined 100 temperature. When the air in the room reaches this temperature from any cause whatever, the yielding of the retaining material will permit the spring to lift the cap and with it the arm and receiver of the 105 telephone which produces a signal in the central office. The spring will act to retain the line open which continues the signal (in effect an alarm) until the line is closed again at the telephone.

In the form illustrated in Fig. 6, the alarm is held in place by a bracket 22 which is

adapted for attachment to a wall or fixture of any kind.

Having thus described my invention, I claim:

5 A fire alarm comprising a case open at one end, a spring therein, an alarm cap adapted to be raised by the spring and having a central depression which passes into the open

end of the case, a depending flange lying at a distance from the case and leaving a ring-shaped space between the flange and the case, and low-melting retaining material in said space, by which the cap is retained in place and the spring held compressed.

In testimony whereof I affix my signature. 15

WALTER H. BOWMAN.
